ROOFING AND VENTILATED ROOF
STRUCTURE

Herman L. Seymour, Jacksonville, Fla., assignor
to The Philip Carey Manufacturing Company,
a corporation of Ohio

Application March 25, 1935, Serial No. 12,776

6 Claims.

(Cl. 108—8)

This invention relates to a novel and improved surfacing unit and also to a novel and improved building construction in which the novel and improved surfacing unit is adapted to cooperate with other elements of the construction to provide ventilation for the building structure. This unit is particularly adapted for roofing where a plurality of them may be laid as the starting and/or finishing course. Or they may be applied as the edge unit in each of the courses.

The surfacing unit or units may be made from metal, asbestos cement and other materials which are formed into relatively thin sheets, and is constructed with a body portion having one end projecting at an angle thereto. The units are particularly adapted for being used as the starting course with the angular projections arranged to overhang the eave or gable and simulate a thickness of roof covering greater than its actual thickness, thereby simulating a more rigid and massive structure than would appear from the actual thickness of the roof covering. Or the roofing units may be employed as the edging course which is associated with a ridge strip and spaced therefrom to provide a watershed ventilating passage between the roof covering and the ridge member.

For a better understanding of the invention reference may be made to the accompanying drawing in which:

Figure 1 is a cross-sectional view of a section of roofing embodying the present invention;

Figure 2 is a cross-sectional view of a roofing section with a novel and improved roofing unit employed as a starting course on a roofing structure;

Figure 3 is a perspective view of a roofing course embodying the present invention;

Figure 4 is a perspective view of a roofing section showing a starting layer.

Referring specifically to the drawing in which like numerals are used to designate like parts, numeral 1 designates a roofing deck composed of wooden planks applied to cover joists 2 which are mounted upon the wall joist 3 of the building frame. Numeral 4 designates a starting course of surfacing units each of which have a body portion 5 provided with a portion 6 projecting at an angle therefrom. This angular portion may be of any conformation but is typified in the drawing as being formed with a circular interior surface 7 and an exterior circular surface 8, this angular projection being adapted to project over the edge of the roof deck and provide a finished edge 9 for the eave and simulates

a roofing covering of much greater thickness than the actual thickness thereof.

The starting course may comprise a single layer of roofing units or a double layer. If a single layer is employed, an undersurfacing of saturated felt or waterproofing covering 10 is necessary in order to protect beneath the joint seams between the roofing units. The felt covering may be applied to underlie the starting course, or it may be applied to underlie the other roofing courses 8' also.

If the starting course comprises a double layer of roofing units, the waterproof covering 10 is optional and may or may not be employed, as desired. If a double layer of roofing units are employed for the starting course they are arranged in off set relation to break joints the same as would be done in laying units of conventional design. A double layer, herein-after described, has been illustrated for the finishing course in Figures 1 and 3, this comprising complementary units having a body portion 4' and an angular projection 5', the latter of which is slightly smaller in diameter so that the angular projections 5' of the complementary course may nest in the angular projections 6 of the main layer. The interior diameter of the complementary unit will be substantially of the same contour as the exterior circumference of the angular portion of the main unit. Shingles 30 of the same size and conformation which are employed for the starting course may also be employed for the finishing course adjacent the ridge.

In the finishing course the angular projections 35 are positioned upwardly and the ridge member 11 is contoured with terminal edges 12 in order to cooperate with the angular portions of the surfacing elements, and provide a watershed when the said elements are associated in spaced 40 relation. The ridge strip may be suitably mounted upon ridge pole 13 by nails 14 and if the nails alone are not sufficient to hold the ridge strip in position further anchoring means in the form of guide rods 15 may be employed, one end being 45 attached to some portion of the ridge strip and the other end being attached to the element.

To prevent birds from having access to the building, a screen 16 may be advantageously employed to cover the ventilating space between the 50 surfacing units and the ridge strip. This screening in the present instance is typified by strip which is fitted between the ridge strip and having its edges projected to engage with the top surface of the roofing. A screening 17 may 55

also be employed at the eave portion for a similar purpose.

While I have illustrated and described one preferred embodiment of the invention it will be understood that there may be various changes 5 in details of the construction without departing from the spirit of the invention.

I claim:

1. A reversible roofing unit adapted to be selectively used in a starting or finishing course comprising a sheet having a body portion provided with a marginal edge projecting at an angle from the body portion and extending to provide a simulated thickness greater than the actual thickness of the body portion, said unit 15 adapted to be laid with the projecting marginal edge disposed toward or away from the surface to be covered, and a separate complementary sheet of similar construction adapted to nest with 20 the first mentioned sheet.

2. A ventilated roof structure comprising a roof deck having a space provided adjacent the eave and ridge, and a roof covering applied to the deck having a terminal portion projecting at an angle from the base portion thereof to cooperate 25 with some portion of the roof to provide a watershed ventilating space at the eave and a watershed ventilating space at the ridge.

3. A ventilated roof structure comprising a roof deck having a space therethrough provided adjacent the ridge and another space at the eave, and a roof covering applied to the deck having 30 a terminal portion projecting at an angle from

the base portion thereof to cooperate with some portion of the roof to provide a watershed ventilating space through the roof and having another portion projecting at an angle to overhang the eave space.

4. A ventilated roof structure comprising a roof deck having a space therethrough provided adjacent the eave, and a roof covering applied to the deck having a terminal portion projecting at an angle from the base portion thereof to 10 cooperate with the space adjacent the eave to provide a watershed ventilating space through the roof.

5. A ventilated roof structure comprising a roof deck having a space provided adjacent the eave and the ridge, and a roof covering applied to the deck having a terminal portion projecting at an angle from the base portion thereof to cooperate 15 with the space adjacent the eave and another angular terminal portion cooperating with the 20 space adjacent the ridge to provide a watershed ventilating passage.

6. In a building structure, a ventilated ridge, a ridge member composed of asbestos cement materials curved so as to cover the ventilating space, asbestos-cement materials applied to the roof adjacent to the ventilating space and curved outward from the roofing in under the cover members so as to form a circuitous passage for 25 the entry of air into the building, an eave vent 30 and asbestos cement shingles applied to the roof adjacent to and overhanging the eave vent.
